UNITED STATES PATENT OFFICE.

WILLIAM H. STINNETT, OF SUGAR LAND, TEXAS.

RECONDITIONING MACHINE.

Application filed May 17, 1928. Serial No. 278,608.

This invention relates to new and useful improvements in a reconditioning machine.

An object of the invention is to provide a machine of the character described specially 5 designed for the purpose of cleansing, disinfecting and reconditioning mattress filler. Mattresses are usually filled with lint cotton, and after a long period of use the filler becomes matted, or packed and also collects dirt 10 and other foreign matter. This filler cannot be cleansed and renewed by washing or scouring in water, as if so washed or scoured it will lose its soft fluffy texture which, when lost, cannot be recovered, and consequently its use 15 as a mattress filler will be destroyed. It is the prime object of this invention to provide a device for so treating this used filler that it will be thoroughly cleansed and disinfected and its life restored, resulting in a renewed 20 product having its original soft and fluffy properties.

Another object of the invention is to provide a device of the character described which is of simple structure, may be cheaply and 25 easily constructed and which is very efficient for the purposes intended.

A further feature of the invention resides in a novel process of treating a used mattress 30 filler in the reconditioning and renewing thereof.

With the above and other objects in view this invention has particular relation to certain novel features of construction, operation and arrangement of parts an example of 35 which is given in this specification and illustrated in the accompanying drawings wherein:—

Figure 1 shows a perspective view of the device.

Figure 2 shows a vertical cross sectional view taken on the line 2—2 of Figure 1.

Figure 3 shows a vertical sectional view taken on the line 3—3 of Figure 2.

Figure 4 shows a partial horizontal sectional view taken on the line 4—4 of Figure 2.

Figure 5 shows a fragmentary vertical sectional view of the curing, or drying, chamber, and

Figure 6 shows a plan view of one of the 50 foraminated shelves employed.

Referring now more particularly to the drawings, wherein like numerals of reference designate similar parts in each of the figures the numeral 1 designates a cabinet, as a whole, 55 which is of a box like structure and which has a central partition 2 separating the same

into a treating, or steaming, chamber 3 and a drying, or curing chamber 4. Corresponding ends of these respective chambers are hinged to the cabinet forming the doors 5, 6. 60

In the steaming chamber 3 are the upstanding steam manifolds 7, 7, one on each side approximately midway between its ends. These manifolds are connected, at their lower ends, into the steam supply line 8, which is 65 controlled by the valve 9. Each manifold has the steam nozzle pipes 10 extending therefrom in opposite directions, said nozzle pipes being spaced apart along the manifolds from the upper to the lower ends thereof, and lying 70 adjacent the partition 2 and the opposing wall of the steaming chamber. Each nozzle pipe has an inside row of nozzle openings 11 slightly inclined upwardly so as to direct the steam issuing through them inwardly and upwardly, as shown in Figure 2. Located between the respective nozzle pipes 10, and arranged one above the other are the removable 75 foraminated shelves 12 whose side margins are supported on the side ledges 13 whose rear 80 ends are anchored to the rear wall of the chamber 3 and whose forward ends are secured to the standards 14.

The filler to be treated is placed on the shelves, outside of the cabinet and the loaded shelves are then inserted into place on the respective ledges 13. Hot steam is then applied by opening the valve 9. This steam is discharged under high pressure against the under side of the respective shelves and 90 passes up through the shelves and the filler thereon, and said filler is thoroughly penetrated, cleansed and disinfected by said steam. The expansion of the steam, in the 95 filler, expands and fills out the compacted, and matted filler and renders the same light and fluffy. After the filler has been thoroughly steamed the loaded shelves are removed and inserted into the curing, or 100 drying, chamber 4 and rest on the side ledges 15 therein. This curing chamber has a heating coil 16 in the bottom thereof to supply heat thereto for curing purposes and its door 6 has an air inlet 17 near the bottom thereof, with a pivotally mounted blow fan disposed inside of the door 6 so as to draw air in through the opening 17 and distribute the same throughout the chamber 4 so as to 105 thoroughly dry and cure the filler therein.

The doors 5, 6 are kept closed during the 110 steaming and curing process and the chambers 3, 4, have the top openings 19, 20, re-

spectively, which may be controlled by the valve like shutters 21, 22. These shutters may be manually moved into open or closed position by the respective shift rods 23, 24.

5 While I have shown what I now consider the preferred form of the invention and the method of using the same it is contemplated that desirable changes may be made therein within the scope of the appended claims.

10 What I claim is:—

1. A device of the character described having two chambers, foraminated shelves spaced apart vertically in said chambers, transverse nozzle pipes between the shelves 15 forming means for delivering steam, under pressure, against the under sides of the shelves in one chamber, each chamber having a top opening and means for controlling said openings.

20 2. A device of the character described comprising separate closed compartments, shelves in each compartment spaced apart vertically, an upstanding inlet manifold on each side of one compartment, transverse nozzle pipes 25 connected into said manifolds and located between the corresponding shelves and provided with nozzle openings directed toward the undersides of the corresponding shelves above.

30 3. The process of reconditioning fibrous material consisting in arranging said material in separate quantities in a closed chamber, introducing hot steam into said chamber between said quantities and circulating said steam through the separate quantities, and thereafter circulating hot dry air through said separate quantities of said material in a 35 closed compartment.

4. A device for reconditioning lint cotton, comprising a chamber, a door at one end thereof, upstanding manifolds within the chamber, one on each side, steam nozzle pipes extending from each manifold in opposite directions, said nozzle pipes being spaced apart along the corresponding manifold and lying adjacent the corresponding chamber wall, each nozzle pipe being provided with an inside row of upwardly directed nozzle openings, side ledges arranged between the respective nozzle pipes whose inner ends are anchored to the corresponding wall of the chamber, standards supporting the forward, or outer ends of said ledges, and removable foraminated shelves supported on said respective ledges.

5. A device for reconditioning lint cotton, comprising a chamber, a door at one end thereof, upstanding manifolds within the chamber, one on each side, steam nozzle pipes extending from each manifold in opposite directions, said nozzle pipes being spaced apart along the corresponding manifold and lying adjacent the corresponding chamber wall, each nozzle pipe being provided with an inside row of upwardly directed nozzle openings, side ledges arranged between the respective nozzle pipes whose inner ends are anchored to the corresponding wall of the chamber, standards supporting the forward, or outer ends of said ledges, removable foraminated shells supported on said respective ledges, and a valve controlled opening in the top of the chamber.

In testimony whereof I have signed my name to this specification.

WILLIAM H. STINNETT.
